WINDOW SCREEN

Filed August 10, 1923

2 Sheets-Sheet 2

UNITED STATES PATENT OFFICE.

JOSEPH BUXTBAUM, OF NEW YORK, N. Y.

WINDOW SCREEN.

Application filed August 10, 1923. Serial No. 656,670.

My invention relates to closures and particularly to window screens.

One object of my invention is to secure a form of window screen that is simple in construction, cheap to manufacture, easily removable, and readily raised to a position allowing one to look out of the window.

Another object of my invention is to permit the screen to fall by its own weight from an open to a closed position, and to become automatically locked thereby.

Still another object is to make it impossible to raise the screen from outside when it is locked without destroying the screen itself or its attachments to the window frame.

A further object is to have the screen so far away from the window that it protects the window panes in case of rain.

Other objects of my invention are to increase ventilation when the screen is in a raised position, and to enable a window cleaner to operate without removing the screen.

Still other objects of my invention will become apparent from the detailed description which follows.

Referring to the drawings, Figure 1 is a front view of my invention.

Figures 2 and 3 are side views in cross section along the line 2—2 of Figure 1, the first one showing this cross section in closed position of the device and the second one being a view thereof when the device is in open position.

Figure 4 is a partial front view of the preferred form of my invention, namely, when the closure is a screen.

Figures 5 to 8 inclusive are details of my preferred and other forms of the device.

In reference to the Figures 1, 2 and 3, various parts thereof will now be described. The frame forming one of the elements of my invention is composed of the upper cross rail 1, the lower cross rail 2, and the two side rails 3, 3. The cross rails, as shown, have a greater depth than the side rails, but this feature is of no particular significance. The frame 1—2—3 may be of any suitable design and in accordance with the material used. Furthermore, it is not necessary to have an extra frame besides the one forming the window frame in a wall opening, and it should be understood that the frame 1—2—3 may be such a window frame, in which case the various attachments and connections described further below would be made di-

rectly on this window frame. The two brackets 4 fastened to the side rails 3 and having fork shaped ends constitute open bearings for the studs 5 on the corresponding brackets 6, the latter being fastened near the top of the closure 7 on either side thereof. The closure 7, which may be a window, a screen, solid boards, or of any suitable character, is composed of two sections, 7' and 7''. The lower edge 8' of sections 7' and the upper edge 8'' of section 7'' slant at complementary angles so that they become contiguous when the closure is in the position shown in Figures 1 and 2. The arms or links 9, which are preferably flexible, are fixedly attached to the sides of 7'', flush therewith, near the edge 8'', and revolvably connected with section 7, near the edge 8', at some point 10. A spring button 11, set into the side of 7' below the point 10, snaps into the opening 12 of the arm 9 when the sections 7' and 7'' assume the closed position shown in Figures 1 and 2. Instead of the spring button and opening 12, I may use a round topped lug 11 and a corresponding depression 12 in the arm 9, the drawing, as shown, being adapted to illustrate either one of these arrangements. The button or lug 11 may be set into the side rail 3 instead of in the section 7', although this variation of the arrangement is not shown in the drawing, being obvious to any one skilled in the art. The vertical or side rails 3 are provided with longitudinal grooves 13 having offset notches 14. The grooves extend high enough to allow section 7'' to be raised to a position where a window cleaner may operate without inconvenience. At the lower end of section 7'', fastened thereto and projecting laterally therefrom, are studs 15 which slidingly fit into the grooves 13 and may rest in the notches 14. At the bottom, section 7'' is provided with a lock 16, shown in detail in Figure 6. The lock 16 comprises a double hooked member 17—17'' revolvable on the pin 18. The end 17'' may engage the stop 20, fastened to the lower cross rail 2, under the action of the spring 19, while the end 17' may be engaged by the finger of an operator. It will be noted that the lock 16 can only be released by compression of the spring 19, i. e. only from inside. The knob 21 on 7'' enables one to control the motion of the sectional closure from an open to a closed position, and vice versa.

In Figure 4 is shown a portion of my preferred form, front view, differing from the form shown in Figures 1 and 2 only in that the closure is specifically a screen.

5 In Figure 5 is shown a different connection between the two sections 7' and 7", namely a hinge 22. It will be noted that the pin 23 of the hinge 22 should be in the center as regards the thickness of the sections 7', 7", in order to balance the motion of the sectional closure when it is allowed to fall from an open to a closed position by its own weight.

10 Another modification of my invention is shown in Figure 7, wherein I add an extra weight 24 to the lower section 7" to facilitate the downward motion of the closure.

15 In Figure 8 is shown a variation of my invention wherein the closure is connected with the upper cross rail 1 by means of a hinge 25, in lieu of the offset pivotal arrangement shown in Figures 1, 2 and 3.

20 The invention is so simple that its operation is almost obvious. The following re-25 marks, however, may be pertinent.

25 Having in mind, principally, the form of my invention which embodies a window screen, the frame 1-2-3 should be set in the wall opening as far away from the window as possible, or, if an existing frame in the opening is utilized, the guiding grooves 13 and pivotal connection between the screen and the window frame at the top should be made as far away from the window as practicable. This will prevent rain from beating on the window panes. It will also increase ventilation. Ventilation is noticeably increased also by the inclined position of the screen sections in open state. The grooves 30 13, by not extending all the way up, prevent the sections from becoming over-inclined and raised to a point where the screen may drop out of its open bearings 4. The off-set form of pivotal connection shown in Figures 1, 40 2 and 3, between the frame and the screen at the top, is preferable to the hinge shown in the Figure 8, as the motion of the screen up and down is more free, owing to greater self adjustability of the various connections 45 and a more effective balancing of the parts. As shown, the closure is complete and tight, the slanting edges 8', 8", constituting a joint impenetrable to flies and other insects. To raise the screen from a closed and locked 50 position, press slightly forward when engaging the hook 17 and pull back when the screen is sufficiently raised, thereby lodging the stud 15 into one of the notches 14. When closing, reverse the operation. In the case 55 of a screen, it is not necessary to lead the sections downward, as one would have to do in the case of a window, to avoid breakage, but the screen may be allowed to fall of its own weight. The moment it reaches the position shown in Figures 1 and 2, the resilient

connection embodied in the arms 9 will cause the two sections to become firmly joined, and at the same time the lock 16 will become operative and set. In this position the screen can not be opened or raised from outside without breaking one of the connections. When the screen is raised, it may be removed from the frame by the mere act of lifting it out of its open bearings 4.

60 My invention is particularly well adapted to light construction of closures of any kind, but I do not mean to limit myself to such light construction, nor to the particular forms illustrated in this specifications. It is to be understood that various omissions, substitutions and changes in the form and details of the device illustrated and its operation may be made by those skilled in the art without departing from the spirit of my invention.

65 I claim:

1. The combination with a frame having side rails, of a sectional closure, means for linking the sections of said sectional closure together, means for holding adjacent edges of said sections in contiguous positions when said sections are flush with one another, which means become released upon said sections moving out of said positions flush with one another, longitudinal guides on said side rails, and means for mounting said sectional closure on said frame, which means comprise and offset pivotal connection at one end of said closure and a sliding member at the other end thereof co-operating with said longitudinal guides.

2. The combination with a frame having side rails, of a screen composed of two sections, means for linking said two sections together, means for holding the adjacent edges of said sections in contiguous positions when said sections are flush with one another, which means become automatically released upon said sections moving out of said positions flush with one another, longitudinal guides on said side rails, means for pivotally suspending said screen offset from said frame, a sliding member on one of said sections co-operating with said longitudinal guides, means for holding said screen in a raised position, and means for locking said screen to said frame, which means are releasable by pressure outward.

3. In a wall opening provided with a window, a frame set in said opening flush with the outer surface of said wall, a sectional screen for said window, and means for removably mounting said screen on said frame, which means comprise a pivotal connection at one end of said screen and a sliding connection at the other end thereof, the axis of said pivotal connection being offset relatively to said sliding connection.

4. The combination with a closure having sections linked for angular motion relatively

- to one another, of a frame therefor, means for revolvably mounting said closure on said frame, means for holding said sections in raised positions at angles to said frame, and 5 guiding means cooperating with said mounting means to cause said closure to assume a position flush with said frame under its own weight upon release from said holding means.
5. The combination with a closure composed of two sections linked for angular motion relatively to one another, of a frame therefor, means for removably mounting said closure on said frame, means for holding said sections in raised positions at angles 10 to said frame, guiding means cooperating with said mounting means to cause said closure to assume a position flush with said frame under its own weight upon release from said holding means, and means for automatically locking said closure to said frame 15 in said flush position.
6. The combination with a closure composed of two sections linked for angular motion relatively to one another, of a frame therefor, means for pivotally mounting said closure on said frame, stops for holding said sections in raised positions at angles to said frame, and a sliding connection between said closure and said frame cooperating with 20 said pivotal mounting to permit said sections to fall of their own weight to closed positions upon release from said stops.
7. The combination with a frame, of a sectional closure, means for linking the sections of said sectional closure together and to said frame for angular motion relatively to one another and to said frame, means for holding said sections at angles to one another and to said frame, resilient means for holding adjacent edges of said sections in contiguous positions when said closure is flush with said frame, means for locking said closure to said frame, and means cooperating with said linking means to cause 30 said closure to become locked when said closure falls of its own weight upon release from said holding means.
8. In a window screen, a closure composed of two sections having slanting edges which are contiguous when said sections are in closed position, connecting links fastened at one end to one of said sections and revolvably attached at the other end to the other one of said sections, and resilient means for holding said slanting edges in a contiguous position. 40
9. The combination with a frame having grooved side rails, of a closure composed of two sections having slanting edges which are contiguous when said sections are flush with said frame, studs on one of said sections and laterally projecting therefrom, offset bearings on said frame for said studs, other studs on the other one of said sections laterally 45 projecting therefrom and slidably fitting
- into said grooved side rails, offset notches on said grooved side rails adapted to receive said other studs, connecting links between said two sections near said slanting edges permitting angular motion of said sections 50 relatively to one another and to said frame, resilient means for holding said slanting edges in contact, and means for automatically locking said closure to said frame when said closure is flush with said frame, which 55 means are releasable by pressure outward.
10. The combination with a frame having side rails, of a screen composed of two sections, longitudinal grooves on said side rails and extending part way their length, slanting edges on said sections which are contiguous when said sections are flush with said frame, studs on one of said sections and laterally projecting therefrom, open bearings 60 for said studs on said frame and offset therefrom, other studs on the other one of said sections laterally projecting therefrom and slidably fitting into said longitudinal grooves, stops on said side rails to hold said sections in raised positions, side links fastened at one end to one of said sections and revolvably connected at the other end to the other one of said sections, resilient means for holding said slanting edges in contact, and locking means becoming operative simultaneously with said resilient means to hold said screen in closed position flush with 65 said frame.
11. The combination with a sectional closure, of a frame, means for linking the sections of said sectional closure to one another and to said frame for angular motion relatively to one another and to said frame, resilient means for holding said sections in 70 positions flush with said frame, and means for automatically locking said closure to said frame, which means become operative simultaneously with said resilient means.
12. The combination with a frame having side rails, of longitudinal grooves on said side rails extending part of their length, a screen composed of two sections, brackets on one of said sections, studs on said brackets and laterally projecting from said section, corresponding brackets on said frame having fork shaped ends serving as bearings for said studs, other studs on the other one of said sections laterally projecting therefrom and slidably fitting into said longitudinal 75 grooves, offset notches on said side rails adapted to receive said other studs, a guiding knob on the face of said screen, resilient connecting links between said sections permitting angular motion of one section relatively to the other and adapted to hold said sections flush with said frame, and means for automatically locking said screen to said frame when said screen assumes a position flush with said frame. 80
